(57) **CLAIM**

The ornamental design for a cutting board holder, as shown and described.

DESCRIPTION

FIG. 1 is a perspective view of a cutting board holder showing the new design,

FIG. 2 is right-side view,

FIG. 3 is a left-side view,

FIG. 4 is a front view thereof,

FIG. 5 is a back view thereof,

FIG. 6 is a top view thereof; and,

FIG. 7 is a bottom view thereof.

The broken lines in the drawings represent portions of the cutting board holder and form no part of the claimed design.
